Filed Jan. 3, 1957, Ser. No. 632,360

2 Claims. (Cl. 211—148)

This invention relates to furniture and particularly to furniture adapted for use in stores, display rooms, filling stations and other places where goods are to be displayed. It relates more particularly to furniture made up of parts which may be shipped knocked down to the location where the furniture is to be installed and there assembled or erected. The cooperating parts of our furniture coact in a novel manner whereby assembly or erection of the furniture is facilitated and the parts are uniquely braced against one another so that the furniture is of rugged and relatively permanent construction.

While certain features of our invention may be otherwise embodied the invention is perhaps best suited for embodiment in a display rack having supporting means and members carried by the supporting means providing a display space for merchandise.

We provide furniture comprising a support having a web having aligned slots therethrough and a member adapted to be connected with the support having aligned projecting lugs adapted to enter the slots, one of the lugs having a recess inwardly spaced from its outer extremity and facing toward the other lug, the width of the bottom of the recess being at least about as great as the thickness of the web, the distance between the bottom of the recess and the nearer edge of the second mentioned lug being approximately the same as the distance between the adjacent edges of the slots, whereby the recessed lug may be first introduced into one of the slots, the member then moved toward the other slot so that a portion of the web enters the recess and the second mentioned lug then introduced into the second mentioned slot. The edge of the recess nearer the outer extremity of the first mentioned lug may be inclined outwardly of the lug toward the second mentioned lug so that as the member is moved toward the second mentioned slot the inclined edge of the recess cooperates with the web to draw the member toward the support. The outer portion of the second mentioned lug nearer the first mentioned lug may be inclined outwardly and away from the first mentioned lug so that after the member has been moved so that a portion of the web enters the recess and the portion of the member in the region of the second mentioned lug is pushed toward the support the inclined edge portion of the second mentioned lug will cooperate with the corresponding edge of the second mentioned slot to guide the second mentioned lug into the second mentioned slot in case of a tight fit.

We further provide furniture comprising a support having a generally horizontal element and a generally vertical element connected with the generally horizontal element at an end thereof and extending generally upwardly therefrom, the generally horizontal element having slot means therein, a member adapted to be assembled to the support having projecting lug means adapted to enter the slot means and proportioned so that an edge of the member substantially abuts the generally vertical element when the lug means are positioned in the slot means, a generally vertical member positioned generally above the

2

first mentioned member and engaging the same adjacent said edge to hold the first mentioned member in position generally atop the generally horizontal element and means connected with the generally vertical element restraining the generally vertical member against upward movement. Preferably two members abutting end to end are adapted to be assembled to the support and have projecting lug means adapted to enter the slot means and are proportioned so that edges of the members substantially abut 10 the generally vertical element when the lug means are positioned in the slot means, and two generally vertical members are provided which are positioned respectively generally above the first mentioned members and engage the same adjacent said edges of the first mentioned members to hold the first mentioned members in position generally atop the generally horizontal element, and means are preferably connected with the generally vertical element and extend about a portion of each of the generally vertical members restraining the generally vertical members against upward movement.

We also provide furniture comprising a support having a generally horizontally oriented element having a generally vertical web and generally horizontal flange means, a pair of members oriented generally horizontally and 25 positioned at opposite sides of said element so as to be supported by the flange means, each of the members having a lug with an opening therethrough, and fastening means extending through lugs of the respective members and through the web of said element maintaining the assembly 30 of the support and members. In a preferred structure the generally horizontally oriented element has generally horizontal flanges at opposite sides of the element at the bottom of the web and each pair of members which are oriented generally horizontally and positioned at opposite 35 sides of the generally horizontally oriented element has a slot receiving one of the flanges of said element whereby the members are supported by the flanges. The lugs desirably project upwardly from the members and the fastening means extend through the lugs generally above 40 the members and through the web of the generally horizontally oriented element maintaining the assembly of the support and members.

We still further provide furniture comprising a support having a generally vertical element and generally horizontal elements each connected at one end with the generally vertical element, one near the top and the other near the bottom of the generally vertical element so that the support is of generally C shape, the lower generally horizontal element having slot means therein, a lower 45 member having lug means supported upon the lower generally horizontal element with the lug means entering the slot means, an upper member supported by the upper generally horizontal element of the support, an intermediate member lying substantially along the generally vertical element of the support and connected with the upper and lower members and holding means carried by the generally vertical element maintaining the intermediate member in position.

Other details, objects and advantages of the invention 50 will become apparent as the following description of a present preferred embodiment thereof proceeds.

In the accompanying drawings we have shown a present preferred embodiment of the invention in which

Figure 1 is a vertical transverse cross-sectional view 55 with portions cut away through a display rack;

Figure 2 is a fragmentary front elevational view of the display rack;

Figure 3 is an enlarged vertical cross-sectional view taken on the line III—III of Figure 1;

Figure 4 is an enlarged horizontal cross-sectional view 60 taken on the line IV—IV of Figure 1;

Figure 5 is an enlarged vertical cross-sectional view taken on the line V—V of Figure 1;

Figure 6 is a perspective view of a support which is one of the parts of the display rack;

Figure 7 is a perspective view of a lug through which parts of the display rack are adapted to be maintained in predetermined relationship when assembled;

Figure 8 is a view similar to Figure 7 of another form of lug also used in the assembly; and

Figure 9 is a perspective view with portions cut away illustrating how elements of the display rack are assembled.

Referring now more particularly to the drawings, the furniture shown therein is a display rack. The display rack comprises supports one of which is designated S (see particularly Figure 6). Preferably a plurality of such supports are employed, the supports being set up in generally parallel spaced apart relationship, the spaces between the supports being determined by the dimensions of the cooperating parts.

Each of the supports S comprises a generally vertical element 2, a lower generally horizontal element 3 and an upper generally horizontal element 4. Each of the elements 3 and 4 is connected at one end with the element 2, one at the bottom and the other at the top of the element 2, as shown in Figure 6, so that the support S is of generally C shape. The elements 3 and 4 may be assembled to the element 2 by suitable interfitting and fastening and/or welding. The support S is preferably made of metal and the elements thereof are preferably welded together.

The series of spaced apart supports S may be fastened directly to the floor or to base boards as shown in Figures 1, 2, 5 and 6. Base boards 6 are shown which may be fastened to the floor in generally parallel relation, and each of the supports S is screwed to the base boards by screws 7 passing through openings 8 drilled in the flanges 9 of the lower elements 3.

The element 3 of each of the supports S is shown in cross section in Figure 5. It is of generally inverted U shape in cross section with the flanges 9 extending outwardly from the feet as shown in Figure 5. Each of the elements 3 has at its top a generally horizontal web 10 through which are formed aligned elongated slots 11 and 12.

The generally vertical element 2 is shown as being hollow (see Figure 4) and preferably has applied to its forward face a vertically continuous generally U shaped bracket 13 as clearly shown in Figure 4. The bracket 13 has flanges 14 which lie against the forward face of the member 2 as shown and the bracket may be welded to the member 2 at the ends of the flanges 14 as shown at 15. In the outer face 16 of the bracket 13 is a vertically aligned series of slots 17 (see Figure 2).

The upper generally horizontal element 4 of each support S is of generally I shape in cross section as shown in Figure 3. The element may be made up of channels disposed back to back as shown in Figure 3 and welded together. Thus there is formed an element having a generally vertical web 18 with generally horizontal flanges 19 projecting laterally from the web 18 in both directions at both the top and the bottom of the web. Spaced openings 20 are drilled through the web.

Adapted to be assembled with the supports S are lower generally horizontal members 21, upper generally horizontal members 22 and intermediate generally vertical members 23. Each of the members 21, 22 and 23 is adapted to span the space between adjacent spaced apart supports S. For example, the spacing on centers between adjacent supports S is preferably substantially equal to the length of the members 21 and 22. The members 23 are of slightly less length as will presently appear.

Each member 21 is in generally the shape of a support or shelf, i.e., planar, but has a recess 24 extending along its upper rear edge as shown in Figure 1. Each member

21 is adapted to have each end supported on the element 3 of one of two spaced apart supports S (see Figure 2). A lug 25 (Figure 7) and a lug 26 (Figure 8) are fastened by screws 27 to the under surface of each member 21 adjacent each end thereof, i.e., there are four lugs, two of each type, fastened to each member 21. Each of the lugs 25 and 26 is of L shape as shown, having a body 28 drilled at 29 to receive the screws 27 and having a downwardly projecting flange 30. The difference between the lugs 25 and 26 is that the flange 30 of each lug 26 has a recess 31 inwardly spaced from its outer extremity and facing toward its companion lug 25 as shown in Figure 1. The lower edge of the recess is inclined as shown at 31a. Of course, the lugs 26 are made in rights and lefts for application to the respective ends of the members 21. Since the flanges 30 of the lugs 25 are symmetrical those lugs do not have to be made in rights and lefts and may be applied at both ends of each of the members 21.

The width of the bottom 32 of the recess 31 of each of the lugs 26 is preferably at least about as great as the thickness of the web 10, as shown in Figure 1. The distance between the bottom 32 of the recess 31 and the nearer edge 33 (Figure 1) of the companion lug 25 is in the case of each pair of lugs 25 and 26 preferably approximately the same as the distance between the adjacent edges of the corresponding slots 11 and 12 whereby each lug 26 may be first introduced into its slot 11, the member 21 then moved toward the slots 12 so that portions of the webs 10 of the elements 3 enter the recesses 31, whereafter the lugs 25 are introduced into their slots 12. Thus so long as the rear ends (i.e., the ends having the recesses 24) of the members 21 are held down against the elements 3 the parts are securely locked together. The outer faces of the flanges 30 of the lugs 25 and 26 are substantially flush with the end faces of the members 21 as shown in Figure 5 so that each slot 11 receives the flanges 30 of two lugs 26 and each slot 12 receives the flanges 30 of two lugs 25. When the member 21 has been introduced into position as above described and as shown in Figure 1 its rearward end substantially abuts the front face of the corresponding member 2. Trim 34 may be applied to each member 21 at the under portion thereof adjacent its forward end for appearance.

The outer portion 33a of the edge 33 of each lug 25 is inclined outwardly (away from the member 21) and away from the companion lug 26 so that after the member 21 has been moved so that a portion of the web 10 of each element 3 enters the corresponding recess 31 and the portions of the member 21 in the region of the lugs 25 are pushed downwardly or toward the elements 3 the inclined edge portions 33a will cooperate with the corresponding edges of the slots 12 into which the lugs 25 are moving to guide the lugs 25 into the slots 12 in case of a tight fit. While in Figure 1 space is shown between the lug 25 and each end of the slot 12, in actual practice the member 21 will usually be in tension between the lugs 25 and 26 and the edge 33 of each lug 25 will be tight against the right hand end of its slot 12 viewing Figure 1. As the member 21 moves toward the left viewing Figure 1 the inclined edge 33a of each lug 26 cooperates with the web 10 of the corresponding element 3 to draw the member 21 toward the element 3. Thus a very tight and firm connection is established between each member 21 and the supports S carrying it.

The upper members 22 also abut end to end in the vertical central plane of the support S as shown in Figure 3. Each of the members 22 has a slot 35 receiving one of the lower flanges 19 of the element 4 as shown in Figure 3, the members 22 being carried by the flanges 19 through the bearing upon the upper faces of the flanges of portions 36 of the members. The members 22 may be assembled with the flanges 19 by relative movement in the direction of the length of the flanges.

Each of the members 22 has projecting upwardly therefrom spaced lugs or a bar 37. The lugs or bar have or has openings or bores 38 therethrough which are in alignment in opposed lugs or bars. Likewise the interposed element 4 has bores 20 therethrough in alignment with the aligned bores 38, and bolts 39 pass through the aligned bores 38 and 20, nuts 40 being applied to the bolts, whereby the members 22 are maintained in assembly with the supports S.

The members 22 have downwardly open slots 41 directly above the recesses 24 in the members 21. The members 23 are put in place with their bottoms in the recesses 24 and their tops in the slots 41 as shown in Figure 1. Each member 23 may be inserted generally upwardly into the corresponding slot 41, moved into place with its edges against the elements 2 as shown in Figure 4 and then allowed to drop into the corresponding recess 24. Lugs 42 which may be of generally angle shape with a slot somewhat like the slot 31 of the lugs 26 may be applied to the bracket 13 by insertion into slots 17 thereof as shown in Figures 2 and 4 to hold the members 23 in place. While in Figure 4 space is shown between the inner face of the lug 42 and the outer face of the corresponding member 23, actually the lugs bear against the members 23 and not only hold them in place but resist any tendency for the rearward portions of the members 21 to rise and disengage the lugs 25 from the slots 12. The members 23 are of considerable extent and of generally planar form and subject to deflection. Any desired number of lugs 42 may be employed and it is found in practice that the lugs have sufficient bearing on or contact with the members 23 to frictionally resist any tendency which may occur in normal use of the furniture for the rearward portions of the members 21 to rise and disengage the lugs 25 from the slots 12.

Any suitable trim, such, for example, as indicated at 43, may be applied to the members 22. In the structure shown the members 22 are hung beneath the elements 4 so as to conceal those elements from the view of persons looking upwardly. If desired the members 22 may be applied to the upper portions of the elements 4, i.e., in inverted position, and still be held in place by the bolts and nuts 39 and 40.

Our furniture as above described is of relatively simple construction and may be rapidly set up and taken down. At the same time it is strong and rugged and of pleasing appearance.

While we have shown and described a present preferred embodiment of the invention it is to be distinctly understood that the invention is not limited thereto but may may be otherwise variously embodied within the scope of the following claims.

We claim:

1. Furniture comprising a support having a web having aligned slots therethrough and a member connected with the support having aligned projecting lugs entering the slots, one of the lugs having a recess inwardly spaced from its outer extremity and facing toward the other lug, the width of the bottom of the recess being at least

about as great as the thickness of the web, the distance between the bottom of the recess and the nearer edge of the second mentioned lug being approximately the same as the distance between the adjacent edges of the slots, the recessed lug being first introduced into one of the slots, the member then moved toward the other slot so that a portion of the web enters the recess and the second mentioned lug then introduced into the second mentioned slot, the edge of the recess nearer the outer extremity of the first mentioned lug being inclined outwardly of the lug toward the second mentioned lug so that as the member is moved toward the second mentioned slot the inclined edge of the recess cooperates with the web to draw the member toward the support.

2. Furniture comprising a support having a web having aligned slots therethrough and a member connected with the support having aligned projecting lugs adapted to enter the slots, one of the lugs having a recess inwardly spaced from its outer extremity and facing toward the other lug, the distance between the bottom of the recess and the near edge of the second mentioned lug being approximately the same as the distance between the adjacent edges of the slots, the recessed lug being first introduced into one of the slots, the member then moved toward the other slot so that a portion of the web enters the recess and the second mentioned lug then introduced into the second mentioned slot, the edge of the recess nearer the outer extremity of the first mentioned lug being inclined outwardly of the lug toward the second mentioned lug so that as the member is moved toward the second mentioned slot the inclined edge of the recess cooperates with the web to draw the member toward the support, the outer portion of the edge of the second mentioned lug nearer the first mentioned lug being inclined outwardly and away from the first mentioned lug so that after the member has been moved so that a portion of the web enters the recess and the portion of the member in the region of the second mentioned lug is pushed toward the support the inclined edge portion of the second mentioned lug will cooperate with the corresponding edge of the second mentioned slot to guide the second mentioned lug into the second mentioned slot in case of a tight fit.
